CLAIM

The ornamental design for an implement head for relocating christmas lights, as shown and described.

DESCRIPTION

FIG. 1 is a front elevational view of the implement head for relocating christmas light showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a reduced perspective view thereof; and,

FIG. 8 is a perspective view thereof.

The broken line portion of FIG. 7 is for illustrative purposes only and forms no part of the claimed design.
